UNITED STATES PATENT OFFICE.

CHRISTIAN MAERTEN, JR., OF NORTH TONAWANDA, NEW YORK, ASSIGNOR TO
ARTIZAN FACTORIES, INC., OF NORTH TONAWANDA, NEW YORK.

AUTOMATIC MUSICAL INSTRUMENT.

Application filed June 16, 1924. Serial No. 720,266.

This invention relates to improvements in automatic musical instruments of that kind in which the playing of the instrument is controlled by a perforated note sheet or element which cooperates with a tracker bar over which it travels to control the operation of pneumatic actuating means for the instrument. More particularly the invention relates to instruments of this kind in which compressed air is used as the operating medium.

In one type of instrument which has heretofore been proposed, the note sheet and the tracker are confined in an air-tight chamber into which the compressed air is introduced in such a manner that when the perforations register with the ducts in the tracker, the compressed air flows in through the perforated sheet and tracker to the controlling or actuating pneumatics or devices for operating the speaking devices.

Various objections attend the use of instruments of this type as, owing to the fact that compressed air passes through the note sheet and tracker, it is necessary to provide screens or dust collectors to rid the air of accumulations of dust, particles of paper from the note sheet and the like, and to make provision for cleaning the screens and removing the accumulations of dust, etc., and a relatively high pressure is required to operate the instrument, which makes necessary the use of considerable power, as, in addition to providing the necessary air pressure for the speaking instruments, additional pressure is required in the chamber for the note sheet and tracker wherewith to operate the actuating devices.

Still other instruments of this character are operated by suction. These instruments, as is well known, are controlled by the relief of the suction by the admission of air at atmospheric pressure through the note sheet perforations and the tracker. Dust collectors or screens are required in these machines for the same reasons stated above. Moreover, a relatively large amount of power is required to operate this type of instrument, as, in addition to the power required to actuate the bellows for compressing air for operating the speaking devices, power is required to operate the suction bellows for the controlling mechanism. Further loss of power results from the fact that, as wood is chiefly used to make the various

ducts and operating parts of the instrument, there is considerable actual leakage of suction through the pores of the wood.

The principal object of the invention is to provide an improved and practical automatic musical instrument in which compressed air is utilized in conjunction with a thin or flexible paper note sheet, and in which the various controlling devices thereof are arranged in a novel manner so as to be actuated by relieving the compressed air outwardly through the tracker ducts and the registering perforations in the note sheet.

Other objects are to simplify and substantially reduce the number of parts of instruments of this sort; also to provide an instrument in which the power required for its operation is reduced to a minimum, and which is easy to operate and is not liable to get out of order; also to provide an improved practical and simple pressure device for yieldingly holding the note sheet on the tracker against the outward pressure of the compressed air; also to provide a simple, practical means for cutting off the supply of compressed air to the various pneumatics and control valves when desired; also to improve and simplify generally, instruments of this kind in the other respects hereinafter specified and claimed.

In the accompanying drawings, which disclose a practical embodiment of the invention:

Fig. 1 is a sectional elevation of the casing, showing the operative parts of an automatic musical instrument, actuated by compressed air in accordance with the invention.

Fig. 2 is a diagrammatically arranged sectional elevation showing the positions of the various controlling pneumatics and devices when the note sheet is moving in playing direction.

Fig. 3 is a similar view of a number of the parts shown in Fig. 2, disclosing the relative operative relation of these parts when the note sheet is being rewound.

Fig. 4 is a sectional elevation of the main cut-off device which controls the supply of compressed air to the various pneumatics and actuating devices of the instrument, showing the same in cutting off position.

Fig. 5 is a fragmentary horizontal section thereof on line 5—5, Fig. 4.

Fig. 6 is a view similar to Figs. 2 and 3, showing the position of the parts when a note sheet perforation is in register with a tracker duct, to sound one of the speaking devices of the instrument.

Figs. 7 and 8 are respectively a horizontal and a vertical section of the diaphragm pouches for the tracker ducts.

Fig. 9 is a face view of the "beginning" and "finish" ends of the note sheet in relation to the tracker.

Figs. 10 and 11 are respectively a plan view and a vertical section of the hand valve for controlling the winding and rewinding mechanism of the instrument independently of the note sheet.

Fig. 12 is a transverse sectional elevation of the valve chest and tracker cut off valve of the instrument on line 12—12, Fig. 2.

Fig. 13 is a similar view of the valve chest on line 13—13, Fig. 2.

Fig. 14 is a sectional elevation thereof on line 14—14 Fig. 12.

Figs. 15 and 16 are horizontal sections thereof on lines 15—15 and 16—16 respectively, Fig. 12.

Fig. 17 is an elevation of a part of the drive mechanism for the note sheet, showing the means for actuating the relief valve for the main cut off device.

Fig. 18 is a transverse vertical section of the tracker, note sheet and note sheet winding and rewinding rolls and the pressure roll for holding the note sheet in contact with the tracker.

Fig. 19 is a plan view of the pressure roll and tracker, partly in section.

Fig. 20 is a fragmentary horizontal section of the tracker, showing a portion of the pressure roll and note sheet in operative relation thereto.

Fig. 21 is a vertical section, on line 21—21, Fig. 19 showing a latch for holding the pressure roll away from the note sheet and tracker.

Fig. 22 is a sectional elevation of one end of the guide carriage for the pressure roll.

The present invention is applicable to instruments having one or more note sheets with a tracker bar and propelling mechanism for each note sheet, but in the arrangement illustrated in the drawings only one note sheet is shown, together with a tracker bar and note sheet winding and rewinding mechanism therefor. The instrument shown is provided with primary pneumatics, winding and rewinding pneumatics, a main cut off device and a tracker cut off valve, together with a valve chest, all of which, while constructed along the lines of similar members disclosed in my copending application for Letters Patent Serial No. 684,715 filed Jan. 7, 1924, are differently arranged to permit them to be actuated through the medium of compressed air. The instrument con-

prises generally the usual wind chest 10, a plurality of pneumatic pouches or diaphragms 11 and pallets 12 actuated thereby for controlling the admission of compressed air from the wind chest to the various speaking instruments or devices, one of which is shown at 13. Compressed air is supplied to the wind chest 10 from the usual pump bellows or reservoirs 14 actuated by link connections 15 from the crank shaft 16 which is rotated from any suitable source of power.

A plurality of primary pneumatics or valve boxes 17, connected with passages 18 leading from the ducts 18^a of the tracker bar A, and controlled by the registration of the note perforations b of the note sheet B with the tracker ducts 18^a, are adapted to admit air pressure to the pouches 11 to open the pallets 12 and thereby cause the instruments 13 to speak. The note sheet B is arranged to be moved over the tracker by a note sheet winding and rewinding mechanism C, which may be of any suitable construction, but which preferably is constructed and adapted to be operated substantially like the note sheet winding and rewinding mechanism shown and described in my copending application for Letters Patent Serial No. 684,715 filed January 7, 1924, that is as follows:

The note sheet, as usual, is secured on a delivery and rewinding roll 20 from which it is adapted to pass over the tracker A and be wound upon a take-up roll 21 to play the instrument. The winding and rewinding mechanism C is adapted to operate these rolls to first move the note sheet B in one direction, as for instance, in the direction of the arrow Fig. 1, for playing the instrument, and to then rewind the note sheet on the roll 20. The mechanism C, includes a supporting frame 22 secured in the instrument as on the shelf D, and the rolls 20, 21 are journaled in the frame and each roll is provided with a clutch device which drives it in one direction and permits it to run free in the opposite direction. A drive shaft 23, journaled in the frame 22 is provided with gears 24, 24^a meshing respectively with a pinion 25 on the shaft of the delivery roll 20, and a gear 26 on a counter-shaft 27. The shaft 27 also carries a pinion 29 meshing with a gear 30 of the shaft for the take-up roll 21. The pinion 25 and gear 30 are loosely journaled and are adapted to move endwise on their shafts, and each of these gears is provided with lateral teeth adapted to engage with teeth on clutch members 31, 32 fixed on the shafts of the rolls 20, 21 respectively. These clutch members 31, 32 and sliding gears 25 and 30 are so arranged and actuated that when either gear is moved to engage its clutch member for rotating its shaft, the other gear will be moved out of engagement with its clutch member. The gear 30 is the winding gear and the

gear 25 is the rewinding gear. The means for alternately actuating these gears for winding and rewinding the note sheet B includes forked arms 33, 34 fixed to a rock 5 shaft 35 journalled in the frame 22 and engaging grooved hubs on the gears 25, 30 so that, by rocking the shaft 35 in opposite directions, the clutches will be alternately moved into and out of position for rotating 10 the rolls 20, 21. The rock shaft 35 is actuated by means hereinafter described. The means for rotating the drive shaft 23 includes a variable speed device E, and means for connecting and disconnecting said device to and from the shaft 23 to start and stop its winding mechanism, while the main 15 drive shaft 16 is running. The drive shaft 16 is geared to and drives a counter shaft 36, which in turn is geared to and drives 20 the variable speed device E. The disconnecting means for the device E includes a bearing slide 37 movable vertically in a guide 38 on the instrument case, and having pivoted thereto one end of a transmission 25 shaft 39, which in turn has a universal joint connection 39^a with an end of the drive shaft 23. The shaft 39 carries a friction wheel 40 adapted to engage a driven cone 41 of the variable speed device E. A crank 30 42 journalled in the case of the instrument is provided with a cam or eccentric 43, see Fig. 17, engaging in an aperture of the bearing slide 37, so that, by turning the crank 42, as by the handle 44, the cam will lift 35 the slide and disengage the friction wheel 40 from the cone 41. The friction wheel is splined on the shaft 39 and is adjustable lengthwise of the shaft 39 for varying the speed of travel of the note sheet, as by means 40 of a rod 45 connected to the hub of the friction wheel and movable axially relatively to said shaft by means of a hand nut 46 or the like, engaging the screw threaded end of the rod at the other side of the instrument 45 case.

The note sheet winding and rewinding mechanism C is provided with a playing or start and stop pneumatic 50 and a rewind pneumatic 51 for operating the clutches of said mechanism, and an automatic tracker cut off mechanism 52 for preventing the speaking of the instrument during the rewinding of the note sheet B over the tracker. These devices are adapted to be actuated by the compressed air under the control of the thin note sheet which acts to relieve the compressed air to actuate said devices by the registration of the note sheet 55 perforations with the tracker ducts. The devices are arranged on a detachable panel 53, secured in the instrument case. The pneumatics 50, 51 are preferably arranged on opposite faces of a bracket 54 secured on the panel 53, see Figs. 1-3, and compressed air is admitted to these pneumatics through

passages 55, 56, in the bracket and connecting passages 57, 58 respectively in the panel 53. The passages 57, 58 connect with ports 59, 60 in a valve chest F, detachably secured on the panel 53, said ports communicating 70 at one end with a compressed air chamber 61 in the valve chest, and at the opposite end opening into the atmosphere at the bottom of the chest. When the instrument is in operation, the chamber 61 is constantly supplied with compressed air from the main bellows or reservoir 14, through a duct 62 leading into a main cut off valve G, and a duct 63 leading from the valve G to a passage 64 in the panel 53 and which opens into 80 the chamber 61.

The pneumatics 50, 51 are coupled together by a bar 70 pivoted to the movable walls of the pneumatics, so that when one of the pneumatics is expanded by the admission of compressed air thereto, the other pneumatic is positively collapsed. This alternating movement of the pneumatics is utilized to actuate the clutches 31, 32 for the note sheet control, preferably by operatively connecting the bar 70 by a link 71 to a fixed arm 72 on the rock shaft 35.

The admission of compressed air to the winding and rewinding pneumatics 50, 51 to alternately operate them, is controlled by 95 means of the valve chest F before mentioned, and ducts 73, 74 in the tracker A, see Fig. 1, which are respectively adapted to cooperate with a winding perforation 75 at the beginning end of the note sheet, and a 100 rewind perforation 76 at the finish end thereof, see Fig. 9.

The port 59 of the valve chest F is adapted to be alternately placed into communication with the chamber 61 and with the atmosphere by means of a playing valve 80 having valve members 81, 82 secured on a stem 83, and the other port 60 is similarly controlled by a rewind valve 84 having valve members 85, 86 on another stem 83. Through 110 the medium of the tracker ducts 73, 74 and the note sheet perforations 75, 76 before mentioned, the valves are alternately actuated to open the ports 59, 60 to the chamber 61 so that compressed air from chamber 61 is admitted alternately to the winding pneumatic 50 by way of port 59 and passages 57 and 55, and to the rewinding pneumatic 51 by way of the other port 60, and passages 58 and 56. Each valve stem 83 passes upwardly through the chamber 61 and its upper end is connected to a dia-phragm or movable wall of a pouch or actuating pneumatic 87. Communication is provided for between the tracker A and the valve chest F for controlling the valves 80, 84, to operate the pneumatics 50, 51 respectively, by means of the tracker ducts 73, 74 before mentioned which are respectively connected to the ports 59, 60 by conduits 92, 92^a 125 130

and 93, 93^a, see Fig. 1. The conduit 92, see Figs. 12 to 16, connects with a passage 94 in a removable cover plate 95, secured to the valve chest by screws or the like, and the passage 94 is provided with a branch passage 96 ending in the port 69, and a branch passage 97 and a bleeder port 98 communicating with the pouch 87 of the playing valve 80. The other conduit 93 is similarly connected to a passage 99, having a branch passage 100 ending in port 59, and a branch passage 101 and bleeder port 102 communicating with the other pouch 87 of the rewind valve 84.

Assuming the parts to be in playing position, as indicated in Figs. 1, 2, 9, 12 and 13, with the note sheet winding on the take up roller 21, the playing pneumatic 50 will be expanded to hold the winding clutch 32 of the mechanism C in driving position, while the rewind pneumatic 51 will be collapsed to hold the rewind clutch 31 in its inoperative position. At the time the winding valve 80 is in position (shown in Fig. 2) to open the port 59 to the compressed air chamber 61 and close it to the atmosphere, and the rewind valve 84 is in position to cut off port 60 from the chamber 61 and open it to the atmosphere. Consequently the compressed air from chamber 61 can pass, by way of ducts 57 and 55 to pneumatic 50 to hold it expanded, while ducts 58 and 56 are open to the atmosphere by way of port 60, thus relieving the pressure in, and permitting the rewind pneumatic 51 to remain collapsed.

As soon however, as rewind perforation 76 of the note sheet registers with the rewind duct 74 of the tracker, the compressed air in the pouch 87 of rewind valve 84 will be relieved by way of conduits 93^a, 93, passage 99, branch 101 and bleeder 102, thus permitting the compressed air in chamber 61 to collapse the diaphragm of the pouch, close the port 60 to the atmosphere by means of valve member 86, and open this port to the chamber 61 by the lifting of member 85. At the same time, the compressed air will enter the port 60 and pass through passages 96, 94, branch 97 and bleeder 98 to the pouch 87 of the winding valve 80, and expand the pouch and lower the valve so as to seal the upper end of port 59 from the chamber 61 and open its lower end to the atmosphere. This results in relieving the winding pneumatic 50 of air pressure, by way of the ducts 55, 57 and port 59. The compressed air in chamber 61, now entering the port 60, will pass there-through by way of ducts 58 and 56 to the rewind pneumatic 51, thereby causing it to expand as shown in Fig. 3. This movement is transmitted through the coupling bar 70 and link 71 to arm 72 of rock shaft 65, causing it to move the rewind clutch 31

to rewinding position and release the winding clutch 32. When the note sheet has been fully rewound the winding perforation 75 thereof will register with the winding duct 73 of the tracker, causing the rewinding pneumatic 51 to be exhausted by the relief of the compressed air therefrom outwardly through port 60, and the relief of pouch 87 of winding valve 80 through the duct 73, conduits 92^a, 92, passage 94, branch 97 and 75 bleeder 98, as before. It is necessary, after the winding valve 80 has been lifted, as explained, to maintain it in such lifted position to prevent the entrance of air into port 59 during the playing of the note sheet, as otherwise the pneumatic might be relieved sufficiently to place the rewind clutch 31 in operative position. A spring 104 is provided in the valve chest F for this purpose, which spring acts on the stem of valve 80 to hold the member 82 against the bottom of port 59. The spring is only strong enough to do this while the pouch 87 of the valve is relieved, and as soon as the perforation 76 registers with duct 74 of the tracker the compressed air will enter the pouch by way of bleeder 98 and the spring will be depressed.

It is desirable to be able to actuate the winding and rewinding clutches for the note sheet at will, independently of the automatic control by the note sheet just described, in order to repeat a desired selection on the note sheet, or to rewind the note sheet and play one or another selection therein without waiting until the end of the note sheet is reached. For this purpose a hand controlled valve H, Fig. 1, is provided. This valve, see Figs. 10 and 11, is formed with a fixed part 106, secured on the shelf D or otherwise, and having a port 107 into which the adjacent ends of the conduits 92, 92^a connect, and a port 108 into which the conduits 93, 93^a connect. A valve member 109 pivotally secured on the part 106, is provided with air ports 110, 111 which are adapted to be brought into register with the ports 107, 108 respectively. These ports 110, 111 are so spaced that only one of them can register with its respective port at one time. The ports 110, 111 correspond, in effect, to the winding and rewinding perforations 75 and 76 and control the winding and rewinding mechanism by the relief of the air out through the hand valve ports, as in the case of said perforations 75 and 76. By swinging the valve member 109 on its pivot in one direction, the ports 107 and 109 will register to actuate the playing pneumatic 50, and by swinging it farther in the same direction the ports 108, 111 will register and actuate the rewind pneumatic 51, by the relief of the air pressure through the described connections of these valves with the valve chest F.

Each of the primary pneumatics 17 before mentioned, is adapted to connect two compressed air passages 112, 113 preferably formed in a panel 114. The passages 112 receive compressed air from a chamber 115 which is under air pressure from the conduit 62, control valve G, and a conduit 116 leading from the control valve to the chamber 115. Each primary pneumatic 17 is 10 provided with a valve 117 arranged in a compressed air chamber 118 communicating with the passage 112, said valve being adapted to normally cut off the chamber 118 from the passage 113 and open this passage 15 to the atmosphere through a port 119. When a note perforation b of the note sheet registers with a note duct 18^a in the tracker A, air pressure in a pouch 120 of the corresponding primary pneumatic escapes outwardly through the registering duct and note sheet perforations, causing the valve 117 to be lifted to close the atmosphere port 119 and establish communication between the 20 passages 112, 113 of that pneumatic and permitting compressed air to pass from the chamber 115 to one of the pouches 11 to depress the pallet 12 for the companion speaking devices 13, see Fig. 6.

Each of the conduits 18 leading from the note ducts 18^a of the tracker, is provided, between the tracker and the primary pneumatic 17, with a cut off diaphragm pouch or device 122, said pouches being preferably all arranged in a diaphragm box 123 secured 30 in the instrument, as beneath the shelf D, see Figs. 1, 2, 7 and 8. The diaphragms 122^a of these pouches are adapted to remain expanded or distended, as shown in Fig. 2, during the time that the note sheet is moving 35 in the playing direction, so that, as the note sheet passes over and opens the ducts 18^a of the tracker, the air pressure in the pouches of the primary pneumatics 17 will be relieved through the conduits 18 by way 40 of the pouches 122 as hereinafter explained. The pouches are constructed and arranged substantially as shown in my application Serial No. 684,715 before mentioned and are not here described in detail.

Means are provided to close the pouch diaphragms 122^a during the rewinding of the note sheet B over the tracker A, so as to prevent the sounding of the speaking instruments during that time. This means, as shown, comprises the cut off valve 52 before mentioned which is preferably similar in operation to the primary pneumatics 17 and comprises a compressed air chamber 124 communicating with the source of compressed air, as by a conduit 125 which connects it with the chamber 61 of the valve chest F. The chamber 124 has a port 126 connected by a conduit 126^a with the pouches 122, and this port is normally closed to the compressed air chamber 124 and is opened 50 to the atmosphere by means of a valve 127, so that, during the playing of the note sheet, air may pass from the back of the pouches by way of conduit 126^a and port 126 to relieve the pressure at that side of the diaphragms 122^a and permit the compressed air from the pneumatics 17 to fill the conduits 18, which conduits can then be relieved by the note sheet perforations as explained. The cut off valve is further provided with a pouch 128 which is normally inflated by compressed air introduced therein by way of a passage 129 leading from the chamber 124 and having a bleeder port 130 communicating with the pouch. 55 The cut off valve 52 is actuated to close the diaphragms 122^a by means of a flap valve 131 arranged to open and close an air duct 132, which connects with the pouch 128. The valve 131 is arranged to close the duct 132 during the playing travel of the note sheet, see Fig. 2, so that the cut off diaphragms 122^a may remain open or distended, and the valve is adapted to open the duct 132 during the rewinding of the note sheet 60 to relieve the pouch 128 and permit the cut off valve 127 to close port 126 to the atmosphere and open it to the compressed air chamber 124, so that compressed air may pass to the cut off pouches 122 by way of conduit 126^a and, by exerting pressure therein, move the pouch diaphragms 122^a against and cut off communication between the adjacent ends of the conduits 18 which enter the diaphragm box 123 and terminate in 65 said diaphragms by sealing said adjacent ends. The duct 132 is preferably arranged in a board 135 secured on the panel 53 adjacent the playing pneumatic 50, so that when this pneumatic is expanded, its movable wall presses a spring strip 133 against the valve 131 and presses the valve against the port to close it to the atmosphere.

When the pneumatics 50, 51 are actuated to move the clutches of mechanism C to rewind the note sheet, the pneumatic 50 moves away from the valve 131 and permits it to uncover the relief port 132, thereby relieving the pouch 128 and causing the diaphragms 122 to be closed as explained, and shown in Fig. 3.

It is desirable that means be provided for cutting off the supply of compressed air to the conduits 63, 116 so that the various pneumatics and other actuating devices of the instrument may be rendered inoperative at will, while nevertheless maintaining air pressure in the wind chest 10, to permit the various speaking instruments or devices 13 to be manually actuated and tested, or for other reasons. The main cut off device G before mentioned is preferably provided for this purpose. This valve is substantially similar in construction and operation to, but of larger capacity than, the primary pneu-

matics 17 and cut off valve 52, and comprises a casing having a compressed air chamber 138 into which the supply conduit 62 leads and an air chamber 139 communicating therewith by a port 140, and with the atmosphere by another port 141. A valve 142 in the device G is adapted to normally close the port 141 and open the port 140 to permit compressed air to pass from the chamber 138 to the chamber 140 and to the conduits 63 and 116 which are connected with the latter chamber. The lower end of the valve 142 is connected to the movable wall or diaphragm of a pouch 143 which is in communication with the chamber 138 by way of a duct 144 and bleeder port 145. The valve 142 is maintained in its lower position by relieving the pouch 143 through the port 144 to the atmosphere, and is raised to close the port 140 and open port 141 by means which prevents the compressed air from being relieved through port 144, thereby allowing the pressure in the pouch 143 to increase and equalize the pressure in said pouch with that in said chambers 138 and 139 and permit the air pressure in chamber 139 to raise the diaphragm thereof and the valve 142. For this purpose the port 144 is connected by a conduit 146 to a relief valve 146^a, which is preferably arranged adjacent the variable speed device E, and having a stem or lever 147 adapted to be actuated by a finger 148 on the crank shaft 42. The finger is positioned so that, when the shaft 42 is actuated to place the friction wheel 40 into engagement with the speed cone 41, it will engage the stem 147 to open the valve and relieve the pouch 143.

When it is desired to cut off the compressed air to prevent actuation of the various pneumatics and control devices, and to stop the winding and rewinding mechanism C, the shaft 42 is actuated to lift the friction wheel 40 off of the cone 41 by means of the cam 43, and at the same time the finger 148 will move away from the stem 147 and permit the valve 146^a to close. The compressed air will now build up in the pouch 143 of the device G and equalize the pressure in said pouch with that of the chambers 138 and 139. This action will cause equal pressure on both sides of the diaphragm and also on both sides of the lower disk member of valve 142, thus neutralizing the action of these parts, but inasmuch as air pressure in the chamber 139 is acting on the lower side of the upper disk of the valve 142, and atmospheric pressure is on the other side of this disk, the pressure in said chamber 139 will be sufficient to raise said upper disk, and consequently the valve 142, to a position in which the lower valve disk will close port 140 and open port 141 to vent the conduits, pneumatics and control devices, so that they will not be inadvertently actuated by a

residue of compressed air left therein, thus preventing the inaccurate positioning of these parts and consequent improper operation of the instrument when it is again started. The valve 142 will now be held in its upper position by the air pressure in chamber 138 as long as the relief valve 147 is closed, as in Fig. 4.

Owing to the fact that a relatively thin paper note sheet is employed, and that the pressure of the compressed air is exerted outwardly through the tracker, means must be provided to maintain the note sheet in close contact with the tracker to prevent the escape or leakage of the compressed air from the tracker behind the note sheet, and to resist the tendency of the compressed air to lift the note from the tracker and thereby prevent its proper operation. A pressure roll 150 is provided for this purpose. This roll 150 preferably comprises a cylindrical body 151 having spaced parallel, relatively thin, annular bearing portions 152 spaced so as to engage the note sheet between the parallel rows of note perforations b therein and press the same against those portions of the tracker A which extend between the ducts 18^a thereof. The pressure roll 150 is supported and caused to bear yieldingly against the note sheet on the tracker in such a way that, should the note sheet be torn, or spliced, or for any reason have parts of unequal thickness, the roll will yield to let such irregular portions pass over the tracker, without causing the stopping of the instrument or tearing the note sheet.

In the embodiment shown in the drawings, see Figs. 18 to 22, these means include a sliding carriage 154 having slide blocks 155 at the opposite ends of the pressure roll in which reduced journals 156 secured to or formed in the ends of the roll 150 bear so as to permit the free rotation of the roll. Each of the slide blocks 155 is formed with oppositely disposed grooves 158 adapted to receive a pair of guide bars 159 on a bracket 160, one of which is secured adjacent each end of the tracker bar A and extends horizontally at right angles thereto, and parallel to each other. In the construction shown, the brackets 160 are secured to forwardly directed lugs 161 of the frame 22 of the mechanism C, and the tracker A may be secured between the opposite inner faces of the brackets, or in any other way. The slide blocks 155 are preferably connected together at their outer ends by a detachable cross bar 162, which completes the carriage 154 and permits movement of either block to be transmitted to the other so as to prevent the blocks from binding in the guide brackets. The pressure roll 150 is thus adapted to move outwardly or away from the tracker by the means described, and said movements are yieldingly resisted, and the

roll held in operative position by means of tension springs 163, one of which is connected to each guide block and to a fixed part of the frame 22, as to the lugs 161, said last 5 connections being in rear of the tracker.

In the present construction, means are also preferably provided for positively holding the pressure roll 156 away from its operative position, against the pull of the springs 10 163 for the purpose of adjusting or inspecting the note sheet and for other reasons. Said means comprises a pivoted latch 164, normally depending from a fixed part of the tracker mechanism as from a pivot 15 bracket or lug 165 on the tracker, and arranged so as not to interfere with the normal operation of the instrument. The latch is provided with a finger 166, and by sliding 20 the carriage away from the tracker to approximately the position shown in Fig. 21, the latch may be swung and the finger engaged behind the cross bar 162 to maintain the roll in retracted position. The latch provides a simple and convenient means for 25 holding the roll out of operative position, but any other suitable device may be provided for this purpose.

By utilizing compressed air for the operation 30 of the control devices and pneumatics of an automatic instrument such as described, having a relatively thin paper note sheet, suction bellows and the necessary pumps, cranks and other connections therefor may be dispensed with, and owing to 35 the fact that the compressed air blows outwardly through the tracker, no dust or particles are sucked into the instrument as in the case of vacuum instruments, and no dust 40 collectors or screening devices are needed. The power necessary for driving the instrument is materially reduced and the compressed air may be supplied from a single reservoir or source for all of the actuating and control devices as well as for the speaking 45 devices.

The provision of a thin paper note sheet 50 enables a relatively light pressure roll to be used, which requires only a slight spring tension to yieldingly maintain it in proper operative relation to the note sheet and tracker.

I claim as my invention:

1. In an automatic musical instrument, the combination of a plurality of speaking 55 devices, individual pneumatic controlling means for each of said devices including a primary pneumatic, a source of compressed air for operating said speaking devices and said pneumatics, a tracker, a perforated note sheet, and a winding roll for moving said note sheet over said tracker, said primary pneumatics being adapted to be automatically actuated for sounding said speaking devices by the relief of the compressed air from said pneumatics outwardly through

said tracker and said note sheet directly to the atmosphere, said speaking devices and primary pneumatics being remote from said tracker and note sheet.

2. In a musical instrument, the combination of speaking devices, a tracker, a perforated note sheet, a winding roll for moving said note sheet over said tracker, pneumatic controlling means for said speaking devices disposed between said speaking devices and said tracker, and a source of compressed air for operating said speaking devices and controlling means, said controlling means being adapted to be actuated for sounding the speaking devices by the relief of the compressed air from said controlling means outwardly through the tracker under the control of the traveling note sheet.

3. In a musical instrument, the combination of speaking devices, pneumatic controlling means for each of said devices, a source of compressed air for operating said speaking devices and said controlling means, a tracker, a perforated note sheet and a winding and rewinding mechanism for moving said note sheet over said tracker alternately in opposite directions, said controlling devices being adapted to be actuated for sounding the speaking devices by the relief of the compressed air outwardly through the tracker when said note sheet is moving in the playing direction, and a tracker cut-off for cutting off the compressed air to the tracker to cause said speaking devices to remain silent when said note sheet is being rewound.

4. In a musical instrument, the combination of a pneumatic playing action, a perforated note sheet controlling said playing action, a tracker, a driving mechanism for said note sheet including a roll on which the note sheet is wound for moving said sheet over said tracker, and a source of compressed air, connections between said source and said playing action whereby said compressed air is operatively connected to said playing action and adapted to operate the same by the relief of said compressed air outwardly through said tracker and note sheet.

5. In a musical instrument, the combination of a pneumatic playing action, a perforated note sheet for controlling said playing action, a tracker, a driving mechanism for said note sheet including a roll on which the note is wound for moving said sheet over said tracker, a source of compressed air operatively connected to said playing action and adapted to operate the same by the relief of said compressed air outwardly through said tracker and note sheet, a starting and stopping device for said note sheet driving mechanism, and a tracker cut-off adapted to be actuated by the starting and stopping device to cut off the flow of compressed air to said tracker.

6. In a musical instrument, the combination of pneumatic speaking devices, pneumatic controlling devices therefor pneumatically connected thereto, a tracker, a perforated note sheet, driving mechanism for said note sheet adapted to move the same over said tracker, pneumatic control devices for said driving mechanism, a source of compressed air for said speaking devices and for said control devices, and an automatic control cut-off device adapted to cut off compressed air to said control devices when said driving mechanism is arrested.

7. In a musical instrument, the combination of pneumatic speaking devices, pneumatically actuated operating devices for causing said devices to speak, pneumatic controlling devices for actuating said operating devices, a tracker, a perforated note sheet, driving mechanism for said note sheet adapted to move the same over said tracker, a mechanical source of power for said driving mechanism, pneumatic control devices for said driving mechanism, a source of compressed air for said speaking devices for said operating devices, and for said control devices, and a control cut-off device adapted to automatically cut off compressed air to said control devices and to vent the pressure therein by the disconnection of said driving mechanism from its source of power.

8. In a musical instrument the combination of a pneumatic playing action, a note sheet in the form of a thin, continuous, perforated strip for controlling said playing action, a tracker, means for moving said note sheet over said tracker, and a source of compressed air operatively connected to said playing action and adapted to operate the same by the relief of said compressed air outwardly through said tracker and note sheet.

9. In a musical instrument the combination of speaking devices, pneumatic controlling means for each of said devices including a primary pneumatic, a source of compressed air for operating said speaking devices and said pneumatics, a tracker, a note sheet in the form of a thin, continuous perforated strip, and means for moving said note sheet over said tracker, said primary pneumatics being adapted to be actuated for sounding said speaking devices by the relief of the compressed air from said pneumatics outwardly through said tracker and said note sheet.

10. In a musical instrument, the combination of pneumatic speaking devices, pneumatically operated actuating devices therefor, pneumatic controlling devices for operating said actuating devices, a tracker, a perforated note sheet, driving mechanism for said note sheet adapted to move the same over said tracker, a mechanical source of

power for said driving mechanism, pneumatic control devices for said driving mechanism, a source of compressed air for said speaking devices, a conduit adapted to supply compressed air from said source to all of said control devices, a control cut-off in said conduit, and means remote from said control cut-off operating, when said driving mechanism is disconnected from its mechanical source of power, to automatically actuate said pneumatic control devices.

11. In a musical instrument, the combination of pneumatic speaking devices, pneumatically operated actuating devices therefor, pneumatic controlling devices for operating said actuating devices, a tracker, a perforated note sheet, driving mechanism for said note sheet adapted to move the same over said tracker, a mechanical source of power for said mechanism, pneumatic control devices for said driving mechanism, a source of compressed air for said speaking devices, a conduit adapted to supply compressed air from said source to all of said control devices, a control cut-off in said conduit including a valve and a pneumatic actuating device therefor, said pneumatic actuating device operating to automatically move said valve to cut off the compressed air to all of said control devices by the disconnection of said driving mechanism from its source of power.

12. In a musical instrument, the combination of pneumatic speaking devices, pneumatically operated actuating devices therefor, pneumatic controlling devices for operating said actuating devices, a tracker, a perforated note sheet and driving mechanism for said note sheet adapted to move the same over said tracker, a mechanical source of power for said mechanism, pneumatic control devices for said driving mechanism, a source of compressed air for said speaking devices, a conduit adapted to conduct compressed air from said source to all of said control devices, an automatic control cut-off in said conduit comprising a casing, a compressed air chamber therein into which said conduit enters, a relief chamber from which said conduit leads to supply the compressed air to said control devices when said instrument is in operation, a port connecting said chambers and a port in said relief chamber connecting it to the atmosphere, a valve in said casing adapted to open said first port and close said second port to permit said compressed air to pass into said relief chamber and through said conduit to said control devices when the instrument is in operation, and means operating automatically by the disconnection of said driving mechanism from its source of power, to move said valve to close said first port to cut off the compressed air to said control devices and to

open said second port to the atmosphere to vent said control devices by way of said conduit and relief chamber.

13. In a musical instrument, the combination of pneumatic speaking devices, pneumatically operated actuating devices therefor, pneumatic controlling devices for operating said actuating devices, a tracker, a perforated note sheet, driving mechanism for said note sheet adapted to move the same over said tracker, a mechanical source of power for said mechanism, means for disconnecting said mechanism from said source of power, a source of compressed air for said speaking devices, a conduit adapted to supply compressed air from said source to all of said control devices, an automatic control cut-off in said conduit including a valve adapted to permit the passage of compressed air through said conduit to said control devices when said instrument is in operation, a pneumatic pouch for actuating said valve, a port remote from said control device which maintains said pouch deflated and open to the atmosphere when said instrument is in operation, and means adapted to close said port to permit said pouch to be expanded by the compressed air in said control cut-off to actuate said valve and cut off the compressed air to said control devices, a part on said driving mechanism disconnecting means which is adapted to automatically act to actuate said port closing means by the disconnection of said driving mechanism from said source of power.

14. In a musical instrument, the combination of pneumatic speaking devices, pneumatically operated actuating devices therefor, pneumatic controlling devices for operating said actuating devices, a tracker, a perforated note sheet, a winding and rewinding mechanism for said note sheet adapted to move said sheet over said tracker, a mechanical source of power for said mechanism, means for disconnecting the same from said mechanism, a pneumatic controlling device for said winding and rewinding mechanism, a source of compressed air for said speaking devices and all of said controlling devices, a tracker cut-off adapted to be automatically actuated by said controlling device for winding and rewinding pneumatic mechanism to cut-off the compressed air to said tracker when said note sheet is being rewound, and an automatic control cut-off adapted to cut off the compressed air to said controlling devices by the disconnection of said winding and rewinding mechanism from said source of power.

15. In a musical instrument, the combination of speaking devices, a tracker, a perforated note sheet, a winding roll for moving said note sheet over said tracker, pneumatic controlling means for said speaking devices disposed between said speaking devices and

said tracker, and a source of compressed air for operating said speaking devices and controlling means, said controlling means being adapted to be actuated for sounding the speaking devices by the relief of the compressed air from said controlling means outwardly through the tracker under the control of the traveling note sheet, and a yielding pressure device adapted to engage a face of said note sheet and hold the same against said tracker in opposition to the pressure exerted by the compressed air against said note sheet.

16. In a musical instrument, the combination of speaking devices, a tracker, a perforated note sheet, a winding roll for moving said note sheet over said tracker, pneumatic controlling means for said speaking devices disposed between said speaking devices and said tracker, a source of compressed air for operating said speaking devices and controlling means, said controlling means being adapted to be actuated for sounding the speaking devices by the relief of the compressed air from said controlling means outwardly through the tracker under the control of the traveling note sheet, and a pressure device having spaced bearing portions adapted to bear on the note sheet between the rows of perforations thereon, and means adapted to hold said pressure device yieldably against said note sheet and hold the note sheet in engagement with said tracker.

17. In a musical instrument, the combination of a pneumatic playing action, a perforated note sheet controlling said playing action, a tracker, a driving mechanism for said note sheet including a roll on which the note sheet is wound for moving said note sheet over said tracker, a source of compressed air operatively connected to said playing action and adapted to operate the same by the relief of said compressed air outwardly through said tracker and note sheet, a pressure roll adapted to bear on and yieldingly press said note sheet against said tracker, journals on said roll, guide blocks for said journals, parallel guide ways to permit said roll to move toward and from said tracker, and means for yieldingly holding said roll in operative position.

18. In a musical instrument, the combination of a pneumatic playing action, a perforated note sheet controlling said playing action, a tracker, a driving mechanism for said note sheet including a winding roll on which the note sheet is wound for moving said sheet over said tracker, a source of compressed air operatively connected with said playing action and adapted to operate the same by the relief of said compressed air outwardly through said tracker and note sheet, a pressure roll adapted to bear on and press said note sheet against said tracker, journals on said roll, a movable

carriage in which said journals bear, said carriage comprising opposite parallel slide blocks and a connecting bar rigidly connecting said slide blocks, fixed guide ways for said blocks, springs for yieldingly holding said roll against said note sheet, and a pivoted latch normally disengaged from said carriage and adapted to be moved to a position in which it will engage said carriage and hold said pressure roll off of said note sheet against the action of said springs, to permit access to said note sheet and tracker.

19. In a musical instrument, the combination of a pneumatic playing action, a perforated note sheet controlling said playing action, a tracker, a driving mechanism for said note sheet including a roll on which the note sheet is wound for moving said sheet over said tracker, a source of compressed air operatively connected to said playing

action and adapted to operate the same by the relief of said compressed air outwardly through said tracker and note sheet, a support on which said driving mechanism, said tracker and said winding roll are adapted to be mounted, a pressure roll adapted to bear on and press said note sheet against said tracker, journals on said roll, a movable carriage in which said journals bear, said carriage comprising opposite parallel slide blocks and a connecting bar rigidly connecting said slide blocks, fixed guide ways for said blocks on said support, springs secured to said carriage and to said support for yieldingly holding said roll against said note sheet, and means for holding said pressure roll out of contact with said note sheet and tracker to permit access thereto.

CHRISTIAN MAERTEN, JR.
